INTERNAL-COMBUSTION POWER UNIT
HAVING A ROTOR WITH PIVOTED IMPULSE ELEMENTS

Orran B. Summers, Morenci, Ariz.

Application April 3, 1944, Serial No. 529,272

12 Claims. (Cl. 123—17)

1

This invention relates to internal combustion power units, and more particularly to an internal combustion power unit of the type wherein a rotor carries at its periphery one or more members, which will herein be called pistons, that are movable into and out of one or more stationary combustion chambers disposed at the periphery of the rotor, said piston or pistons operating to transmit to the rotor impulses derived from the combustion of fuel in said combustion chamber or chambers while the piston or pistons are making an excursion through said chamber or chambers.

Various proposals have heretofore been made to construct an internal combustion engine in the form of a rotor carrying a plurality of hinged pistons which are cam actuated for movement into and out of combustion chambers disposed in or around the periphery of the rotor. Devices of this type as heretofore proposed have been characterized by low efficiency owing to the back thrust exerted on the rotor during the period of combustion and the angle at which the forward thrust has been transmitted to the rotor during the period of combustion. Devices of this type as heretofore proposed have also been unsatisfactory for other reasons, among which may be noted the excessive rate of movement required of the hinged piston with respect to the rotor as it moved into or out of the combustion chamber whereby a rather sharp limitation was imposed upon the rate of revolution of the rotor to avoid an undue total speed of the hinged piston; the combustion chambers have been so shaped that it has been difficult if possible for the hinged piston to follow closely the contour of the combustion chamber so that gas leakage, unsatisfactory scavenging, etc. have resulted; the hinged pistons have been difficult to lubricate; etc.

It is an object of this invention to provide a rotating power unit of the type referred to which is possessed of higher efficiency than obtained by units of this type as heretofore proposed.

Another object of this invention is to provide an improved power unit of the type characterized wherein the pistons are so constructed and associated with the rotor that minimum back thrust is developed on the rotor during the period of combustion and the forward thrust generated on the piston is so transmitted to the rotor as to develop maximum driving torque.

Another object of this invention is to provide an improved rotating power unit of the type characterized which is so constructed that the rate of movement of the piston with respect to the

2

rotor is such that at no time is its absolute rate of movement much greater than the rate of revolution of the rotor, so that the movement of the piston with respect to the rotor into and out of the combustion chamber does not impose a limitation upon the speed at which the rotor may be driven.

Another object of this invention is to provide an improved rotating power unit of the type characterized wherein the piston is caused to closely follow the contour of the combustion chamber so that leakage of gases is avoided, good scavenging action is obtained and efficient transmission to the rotor of the force generated by the expanding gases of combustion is secured.

Another object of this invention is to provide an improved rotating power unit of the type characterized which facilitates proper lubrication of the parts.

20 Another object of this invention is to provide an improved rotating power unit of the type characterized which is so constructed that such lateral thrust as exists on the rotor is at all times substantially balanced.

25 Another object of this invention is to provide an improved rotating power unit of the type characterized which is so constructed that the impulses derived from the combustion of the fuel occur at such frequency that the effect of a nearly constant rotating torque is obtained.

Another object of this invention is to provide an improved rotating power unit which is simple in construction, inexpensive to maintain, and efficient in operation.

30 Other objects will appear as the description of the invention proceeds.

The invention is capable of receiving a variety of mechanical expressions one of which is shown rather diagrammatically on the accompanying drawings, parts like valves and their actuators, manifolds, ignition system, timing system and the like, which are more or less conventional in internal combustion power units, having been omitted or merely indicated in the interest of a clearer illustration of the novel features which characterize the present invention. Hence it is to be expressly understood that the drawings are for purposes of illustration only and are not to be construed as a definition of the limits of the invention, reference being had to the appended claims for that purpose.

Referring in detail to the drawings wherein the same reference characters are employed to designate corresponding parts in both figures,

55 Fig. 1 is a vertical section transversely of the

shaft taken through the rotor and combustion chamber on the line 1—1 of Fig. 2, and

Fig. 2 is a side elevation, partly in section, of an embodiment of the present invention.

In the form shown, 10 designates any suitable bed plate on which is mounted in any appropriate way a bracket 11 of any suitable construction and of appropriate strength and rigidity to support the stationary parts of the power unit. As illustrated the bracket 11 is of generally rectangular shape and braced at its angles by diagonal members 12 which may be attached to the uprights and upper transverse member 13 in any suitable way. Rigidly attached to the bed plate 10 and the bracket 11 is a stationary supporting ring 14 for the combustion chambers, said ring being of any suitable construction. As illustrated said ring is of T-shaped cross section, and is mounted on the base 10 by brackets 15 and attached at 16 in any suitable way to the uprights and transverse member 13 and the diagonal bracing members 12 of said bracket.

Ring 14 constitutes a support for one or more stationary combustion chambers. A plurality of combustion chambers is preferably employed for a purpose that will appear from the description of operation, and in the preferred form of the present invention an even number of combustion chambers is used with said chambers disposed symmetrically around the axis of the ring, four being down. As all of the combustion chambers are alike it will be sufficient to describe one. Each chamber is rectangular in cross section, having a peripheral wall 19 which is attached to the ring 14 in any suitable way, as by flanges 20 which may be riveted, spot welded or otherwise secured to the sides of the ring 14, and side walls 21 which may be integral with or suitably attached to the peripheral wall 19. The contour of the combustion chamber in planes at right angles to the axis of the ring is such that there is symmetry with respect to a radial plane midway of the length of the chamber circumferentially, and the peripheral wall has its inner surface curved in the direction of the circumference of the ring so that there are approximately equal increments or decrements in the altitude of the arc (measured from the inner periphery of the ring) for equal increments of distance in the direction of the circumference of the ring.

Also mounted on the base 10 and attached thereto in any suitable way are pedestals 22, one at either side of the ring 14, and mounted in said pedestals by means of any suitable bearings is a shaft 23. Suitably secured to said shaft 23 is a rotor shown as in the form of a hollow drum having end walls 24 and 25 and a peripheral wall 26. Peripheral wall 26 is shown as provided with a plurality of apertures 27 corresponding in number to the combustion chambers disposed symmetrically around the same, and mounted in each aperture 27 is a piston 28, here shown as of generally triangular configuration in cross section, and if preferred of hollow construction, each piston 28 having an axial width equal to the space between the walls 24 and 25 of the combustion chamber and being of rectangular cross section in radial planes. Each piston 28 is pivoted at 29 to the peripheral wall 26, and carries a cam follower in the form of a transverse pin 30, and to permit the movement of the piston 28 into and out of the combustion chambers 18 the side walls of the rotor opposite each piston are provided with arcuate slots 31 struck about the pivot pins 29 as centers.

Disposed exteriorly of the rotor is cam means for moving the pistons 28 into and out of the combustion chambers 18. While only one cam plate need be used, two cam plates 32 are preferably employed, one at each side of the rotor, so that the cam follower 30 is operated from both ends. The cam plates 32 are supported in any suitable way, being here shown as carried at their upper extremities by a U-shaped bracket 33 which is attached to the transverse member 13 of bracket 11 and has depending arms to which the cam plates 32 are suitably secured as shown at 34. To give proper rigidity to said cam plates, they are also preferably attached to the pedestals 22 adjacent their lower extremities as shown at 35. Each cam plate is provided with a cam groove 36 as shown in elevation in Fig. 1, said cam groove having as many cusps 37 as there are pistons and combustion chambers, and said cusps 37 being connected by short sections 38 which are concentric with the axis of the rotor. The pin 30 constituting the cam follower may be provided with any suitable antifriction means for coaction with the cam grooves 36, and said cam grooves and follower may be lubricated in any suitable way.

Each combustion chamber is provided with an exhaust port 39 communicating with any suitable exhaust manifold 40. Each combustion chamber is also provided with suitable inlet means for the combustible mixture and with ignition means. The mixture of air and fuel may be effected outside of the combustion chambers and injected into the combustion chambers, but as shown each combustion chamber has a fuel admission valve 41 controlling a fuel inlet port, in communication with a suitable manifold 42 through which the fuel may be either injected or sucked as hereinafter explained, and an air admission valve 43 for controlling an air inlet port, in communication with a suitable manifold 44 for supplying air under pressure as hereinafter explained. Each combustion chamber is also provided with an ignition means, such as a suitable spark plug diagrammatically indicated at 45.

For supplying compressed air, any suitable air compressor may be used, but as shown in Fig. 2 a duplicate of the construction so far described may be employed as an air compressor. To this end a third pedestal 22 is carried by the base 10 and the shaft 23 is extended and supported therein. Shaft 23 carries a second drum-like rotor 46 like the rotor 24, 25, 26 of the power unit, said rotor carrying pistons 28 operated by cam grooves 36, while a bracket 47, like bracket 11, supports a stationary ring 48, like ring 14, carrying a plurality of chambers, like the chamber 18, with which cooperate said pistons. In fact the parts of the compressor may be of identical construction with the parts of the power unit described except that no ignition means is provided, the two inlet valves 41 and 43 are replaced by a single open inlet port comparable to the port 39, and the port 39 is replaced by a single air outlet valve controlling a port in communication with a manifold for conveying the compressed air to the manifold 44 heretofore referred to.

In operation, as the rotor turns with the shaft 23 each cam follower 30, as it follows the cam grooves 36, gradually and progressively moves its corresponding piston 28 through its aperture 27 into and out of each combustion chamber 18 in succession. Each cusp 37 is so shaped and dis-

posed with respect to its corresponding combustion chamber 18 that movement of the corresponding piston 28 outwardly through the aperture 27 is initiated at the instant when the extremity 49 of the piston reaches the beginning 50 of the curve defining the inner peripheral contour of the combustion chamber 18, it being assumed that the rotor is rotating in the direction indicated by the arrow 51. Each cusp 37 is also so shaped that the extremity 49 of the piston as it moves radially outward is maintained in close contact with the inner surface of the wall 19 throughout the excursion of the piston through the chamber. Thus as the piston moves circumferentially with the rotor, it moves gradually into the chamber until it has reached the midpoint in the length of the chamber, after which the piston is withdrawn gradually through the aperture 27, but with the extremity 49 continuing to remain in contact with said inner surface, until it reaches the end of the combustion chamber. Owing to the character of the curvature of the surface 19 as above explained the movement of the piston is substantially uniform throughout, the piston at no time having an abrupt or sudden movement, and its rate of movement into and out of the combustion chamber is so gradual that it does not add to the circumferential motion of the piston with the rotor a sufficient amount to require that a limit be imposed upon the speed of revolution of the rotor in order that the absolute rate of movement of the piston shall not be excessive.

As the piston moves past the fuel inlet valve 41 a suction is created at the left-hand end of the combustion chamber as viewed in the drawings, and fuel is drawn into the combustion chamber by the suction created by the rotating piston for such time as the inlet fuel valve remains open. While suction may be relied upon entirely for drawing fuel into the combustion chamber, the fuel may be supplied under pressure and injected in well known ways if preferred. When the piston has moved past the air inlet valve 43, the latter is opened to admit compressed air into the combustion chamber, the air being at such a pressure as to obtain the desired "compression" in the mixture of fuel and air before ignition. The fuel is then ignited by a spark from the spark plug 45 and the resulting explosion develops a driving impulse on the face 52 of the piston. This pressure at the face of the piston is applied through the pivot pin 29 to the rotor and in a direction which is nearly tangential to its peripheral wall, driving the rotor forwardly in the direction of the arrow 51. The combustion space increases in radial dimension until the mid-point of the combustion chamber is reached by the extremity 49 of the piston, after which the combustion chamber decreases in radial dimension as the piston 28 is withdrawn through the aperture 27, until it is flush with the periphery of the rotor when the end 53 of the combustion chamber is reached. Throughout its excursion through the combustion chamber the piston fills the cross section thereof because in radial planes it is of the same size and shape as the chamber. The cam follower 30, when the piston is withdrawn from the chamber, enters the dwell 38, and during this time the piston is substantially entirely within the hollow interior of the drum, with its side wall filling the aperture 27, at which time lubrication of the piston and associated parts is facilitated. Then when the cam follower 30 reaches the next cusp

37, the piston is moved into the next chamber 18 and the cycle is repeated.

When the piston leaves the combustion chamber it uncovers the exhaust port 39 so that the 5 burnt gases in the combustion chamber may escape therethrough, and when the next piston 28 makes its excursion through this combustion chamber, the burnt gases are swept ahead of it and through the exhaust port 39 until the piston 10 passes the exhaust port.

In the compressor 46, 48, which as before noted 15 is identical in construction with the combustion unit under description except for the valves, the pistons 28 are passing through corresponding cycles of movement, but here the suction of the moving piston is drawing air into each chamber 18, after which the succeeding piston sweeps the air ahead of it and places said air under compression until, at the proper pressure, the valve 20 is opened to permit the compressed air to flow into the manifold leading to the air inlet manifold of the power unit.

As the parts of the power unit are surrounded 25 on all sides by air, the rate of heat loss from the walls of the unit is relatively large so that air cooling is facilitated. However, if preferred a water jacket (not shown) may be provided for the combustion chambers.

Escape of gases between the cooperating rotatable 30 and stationary surfaces of the unit may be prevented in any suitable way. As illustrated more particularly in Fig. 2, the end walls 24 and 25 of the rotor overlap the side walls 21 of the combustion chambers as shown at 54, and any 35 suitable packing may be provided between these cooperating rotatable and stationary surfaces. Appropriate packing may also be provided at each piston so as to prevent escape of gases from the combustion chambers into the interior of the 40 rotor.

As before noted, each piston is withdrawn into the interior of the rotor for a period before its movement into the next combustion chamber. This facilitates lubricating the piston, and it is 45 to be understood that any suitable provision for lubricating the pistons and their associated parts may be provided.

It will be noted that owing to the shape of the 50 combustion chambers movement of the pistons at all times is gradual and substantially uniform. Hence there is no sudden change of speed in the movement of the pistons or period at which their movement is much greater than the movement of the rotor to which they are attached. 55 Throughout the period when the expanding gases are exerting a driving force on the piston, there is no surface on which said gases exert a pressure in the direction opposite to that in which the rotor is rotating, and therefore the driving 60 torque is not diminished by back pressure. Furthermore, the pressure on the piston delivered through the piston to its pivot at the periphery of the rotor is acting very nearly in the direction of the tangent to the rotor, so that the component of force at right angles to the tangent is at all times relatively low, a fact which means relatively high efficiency in developing the rotating 65 torque. As before noted a power unit embodying the present invention preferably has an even 70 number of combustion chambers arranged symmetrically around the axis of the shaft, so that there are diametrically opposed combustion chambers in operation at the same time. As the timing is such that the same point in the cycle of 75 operation of each pair of opposed chambers is

reached simultaneously, the component of force at right angles to the tangent at each chamber is exactly balanced by a like component acting in the opposite direction from the opposite combustion chamber. Hence there is never a resultant side thrust on the shaft.

In the form shown there are four combustion chambers having four pistons so that there are four simultaneous driving impulses imparted to the rotor each time the four pistons come into cooperative relationship with the four combustion chambers, producing sixteen driving impulses per revolution. Hence the driving impulses not only occur symmetrically around the periphery of the rotor but a plurality of times per revolution so that by using a suitable number of combustion chambers and cooperating pistons it is possible to nearly approximate a uniform driving torque. Some of the advantages of my invention may be had by using an odd number of combustion chambers, or even using only a single combustion chamber, but I prefer to use an even number of combustion chambers, and while two combustion chambers may be sufficient for some purposes, I prefer to use four or more combustion chambers so as to shorten the period between the application of successive driving impulses to the shaft.

It will therefore be perceived that the present invention provides an improved internal combustion rotating power unit which satisfies each and all of the objects above set out.

While the embodiment of the invention illustrated on the drawings has been described with considerable particularity it is to be expressly understood that the invention is not restricted thereto, as the invention is capable of receiving a variety of mechanical expressions, as will now be apparent to those skilled in the art, while changes may be made in details of construction without departing from the present invention. It is to be understood that the engine is to be provided with suitable means for operating the valves at proper intervals, for energizing the spark plugs at proper intervals, for lubricating the relatively movable cooperating parts, for packing the joints between relatively removable cooperating parts, etc., as would be applied by one skilled in the art in carrying out the foregoing principles, the drawings being for the purpose of illustrating diagrammatically the features of novelty rather than all of the details of construction and accessories that would normally be applied to such a unit by one skilled in the art. Reference is therefore to be had to the appended claims for a definition of the invention.

What is claimed is:

1. In an internal combustion power unit the combination of a rotor, a generally triangular-shaped piston pivotally mounted at an apex on the periphery of said rotor for applying thrust thereto, said piston having its explosion receiving face at all times approximately normal to the tangent to the periphery of said rotor at said pivotal mounting, a stationary support, a combustion chamber mounted on said support in circumferential alignment with the periphery of said rotor, said combustion chamber in circumferential cross section having its radially outer wall gradually curved circumferentially and symmetrically from an intermediate point to both extremities with the altitude of said outer wall above the inner periphery of said chamber first increasing and then decreasing by substantially equal amounts for equal distances in the direc-

tion of the length of said chamber, a cam follower carried by a second apex of the piston, and a single cam means cooperating with the cam follower to move the piston into and out of the combustion chamber while maintaining continuous contact with said outer wall.

2. In an internal combustion power unit the combination of a rotor, a generally triangular-shaped piston pivotally mounted at an apex on the periphery of said rotor for applying thrust thereto, said piston having its explosion receiving face at all times approximately normal to the tangent to the periphery of said rotor at said pivotal mounting, a stationary support, a combustion chamber mounted on said support in circumferential alignment with the periphery of said rotor, said combustion chamber having a circumferentially curved radially outer wall whose altitude above the inner periphery of the chamber first gradually increases and then gradually decreases symmetrically with respect to its medial radial plane, the increments and decrements of altitude being substantially equal for equal distances circumferentially of the chamber, a cam follower carried by a second apex of the piston, and a single cam means of the same contour as said outer wall cooperating with the cam follower to move the piston into and out of the combustion chamber in continuous gas sealing relationship to said outer wall.

3. In an internal combustion power unit the combination of a hollow rotor having an aperture in its peripheral wall and a chamber interiorly thereof, a generally triangular-shaped piston pivotally mounted at an apex in said aperture substantially at the periphery of the rotor for applying thrust thereto and having its explosion receiving face approximately at right angles to the tangent to said periphery at said pivotal mounting so that the force generated at the face of the piston by the combustion of the fuel is applied to said rotor nearly tangentially thereof, a stationary support, a combustion chamber having a circumferentially and symmetrically curved radially outer wall mounted on said support in circumferential alignment with the periphery of said rotor with the altitude of said outer wall above the inner periphery of said chamber first increasing and then decreasing by substantially equal amounts for equal distances in the direction of the length of said chamber, a cam follower carried by the piston, and cam means cooperating with the cam follower to move the piston into and out of the combustion chamber in continuous cooperative relationship with said outer wall, the major portion of said piston when moved out of said combustion chamber being exposed for lubrication in said first named chamber.

4. In an internal combustion power unit the combination of a rotor having a hollow interior and provided in its peripheral wall with an aperture, a generally triangular-shaped piston pivotally mounted at an apex in said aperture for applying thrust thereto and having a side wall adapted to fill said aperture, said piston having its explosion receiving face approximately at right angles to the tangent to said peripheral wall at said pivotal mounting, a stationary support, a combustion chamber mounted on said support in circumferential alignment with the periphery of said rotor, said combustion chamber having a circumferentially curved radially outer wall whose altitude above the inner periphery of the chamber first gradually increases and then gradually decreases by approximately equal

amounts for equal distances circumferentially of the chamber, a cam follower carried by a second apex of the piston, and cam means cooperating with the cam follower to move the piston gradually and progressively first into and then out of the combustion chamber in continuous cooperative relationship with said outer wall, said piston when moved out of said combustion chamber being largely exposed in the hollow interior of said rotor.

5. In an internal combustion power unit the combination of a rotor, a generally-triangular-shaped piston pivotally mounted at an apex on the periphery of said rotor for applying thrust thereto, said piston having its explosion receiving face at all times approximately normal to the tangent to the periphery of said rotor at said pivotal mounting, a stationary support, a combustion chamber having a circumferentially and symmetrically curved radially outer wall mounted on said support in circumferential alignment with the periphery of said rotor with the altitude of said outer wall above the inner periphery of said chamber first increasing and then decreasing by substantially equal amounts for equal distances in the direction of the length of said chamber, a cam follower carried by a second apex of the piston, and a single cam means cooperating with the cam follower to move the piston into and out of the combustion chamber with its radially outer extremity following said outer wall, said cam means comprising a pair of cam plates disposed exteriorly of said rotor one at each side of said rotor and said cam follower projecting through the opposite sides of said rotor into cooperative relationship with said cam plates.

6. In an internal combustion power unit the combination of a rotor, a plurality of generally-triangular-shaped pistons pivoted at an apex on the periphery of said rotor and disposed symmetrically around said periphery, each of said pistons having an explosion receiving face approximately at right angles to the tangent to said periphery at said pivot and exerting a thrust on said rotor approximately in the direction of said tangent, a stationary support, a plurality of combustion chambers equal in number to said pistons mounted on said stationary support and disposed symmetrically around the periphery of said rotor, each of said combustion chambers having a gradually curved radially outer wall which is symmetrical with respect to a radial plane midway of the length of the chamber and has the altitude of its curved wall from its inner periphery first increasing and then decreasing by substantially equal amounts for equal circumferential distances, each of said pistons being provided with a cam follower at a second apex thereof, and a single cam means cooperating with said cam followers and adapted to move all of said pistons into and out of all of said chambers simultaneously with the outer extremities of the pistons following said outer walls.

7. In an internal combustion power unit the combination of a rotor, a plurality of generally-triangular-shaped pistons pivoted at an apex on the periphery of said rotor and disposed symmetrically around said periphery, each of said pistons having an explosion receiving face approximately at right angles to the tangent to said periphery at said pivot and exerting a thrust on said rotor approximately in the direction of said tangent, a stationary support, a plurality of combustion chambers equal in number to said pistons mounted on said stationary support and

disposed symmetrically around the periphery of said rotor, each of said chambers having a radially outer curved peripheral wall whose altitude above the inner periphery of the chamber first increases and then decreases by substantially equal amounts for equal distances in the direction of the length of the chamber, each of said pistons being provided with a cam follower, and cam means cooperating with said cam followers and adapted to move all of said pistons into and out of all of said chambers simultaneously with the outer extremities of said pistons following said outer walls.

8. In an internal combustion power unit the combination of a rotor, a plurality of pistons approximately triangular in circumferential cross section and substantially rectangular in radial cross section pivoted at an apex on the periphery of said rotor and disposed symmetrically around said periphery for applying thrust to said rotor, each of said pistons having an explosion receiving face approximately at right angles to the tangent to said periphery at said pivot, a stationary support, a plurality of combustion chambers equal in number to said pistons mounted on said stationary support and disposed symmetrically around the periphery of said rotor, said chamber and pistons being arranged around the axis of said rotor to provide balanced forces in both vertical and horizontal directions, each of said chambers having a circumferentially curved radially outer wall which is symmetrical with respect to a medial radial plane and has the altitude of its outer wall above its inner periphery first increasing and then decreasing by substantially equal amounts for equal circumferential distances, each of said pistons being provided with a cam follower, and a single cam means cooperating with said cam followers and adapted to move all of said pistons into and out of all of said chambers simultaneously with the outer extremities of said pistons following said outer walls.

9. In an internal combustion power unit the combination of a rotor in the form of a drum provided in its peripheral wall with apertures disposed symmetrically around said periphery, a stationary support, a piston for applying thrust to said rotor having an approximately triangular circumferential cross section pivoted at an apex in each aperture and having an explosion receiving face approximately at right angles to the tangent to said rotor at said pivot, said piston having a side wall which fills the aperture when the piston is withdrawn into the drum, a plurality of combustion chambers equal in number to said pistons mounted on said stationary support and disposed symmetrically around the periphery of said rotor, each of said chambers having a circumferentially curved radially outer wall whose altitude above the inner periphery of the chamber first gradually increases and then gradually decreases circumferentially of the chamber substantially equal amounts for equal distances in the direction of the length of the chamber, each of said pistons being provided with a cam follower at another of its apexes, and a single cam means cooperating with said cam followers and adapted to move all of said pistons into and out of all of said chambers simultaneously with said pistons having the third apex following said outer walls.

10. In an internal combustion power unit the combination of a rotor, a plurality of pistons pivoted at the periphery of said rotor for applying thrust thereto and disposed symmetrically around

said periphery, each of said pistons being of generally triangular form pivoted at an apex and having an explosion receiving face remote from said pivot and approximately at right angles to the tangent to said rotor at said pivot, a stationary support, a plurality of combustion chambers equal in number to said pistons mounted on said stationary support and disposed symmetrically around the periphery of said rotor, each of said chambers having a curved outer wall whose altitude above its inner periphery first increases and then decreases by substantially equal amounts for equal distances in the direction of the length of said chamber, each of said pistons being provided with a cam follower at a second apex thereof, and a single cam means cooperating with all of said cam followers and adapted to move all of said pistons into and out of all of said chambers simultaneously with the outer extremities of the pistons following said outer walls, said cam means comprising a pair of cam plates disposed exteriorly of said rotor one at each side of said rotor and said cam followers projecting through both lateral walls of said rotor into cooperative relationship with said cam plates.

11. In an internal combustion power unit the combination of a rotor provided with an even number of pistons pivoted in the peripheral wall of said rotor, a stationary support, an even number of combustion chambers, each of said pistons being of generally triangular form pivoted at an apex and having an explosion receiving face remote from said pivot and approximately at right angles to the tangent to said rotor at said pivot, said chambers being the same in number as said pistons and carried by said stationary support and disposed symmetrically around the periphery of said rotor, each of said combustion chambers having a curved radially outer peripheral wall whose curvature is such that a piston maintained in contact with said curved wall moves substantially equal increments into or out of the chamber for equal increments of movement of rotation, each of said pistons being provided with a cam follower, and cam means cooperating with said followers and adapted to move diametrically opposed pistons into and out of diametrically opposed combustion chambers simultaneously, said cam means cooperating with said pistons to retain the outer extremity of each piston in contact with a peripheral wall throughout the excursion of a piston through a combustion chamber.

12. In an internal combustion power unit the combination of a rotor provided with an even number of pistons pivoted in apertures in the peripheral wall of said rotor, each of said pistons being approximately triangular in circumferential cross section and pivoted at one of its apexes and having an explosion receiving face remote from said pivot and approximately at a right angle to the tangent to the rotor at said pivot, a stationary support, an even number of combustion chambers, equal in number to said pistons, carried by said stationary support and disposed symmetrically around the periphery of said rotor, each of said combustion chambers having a curved radially outer peripheral wall whose curvature is such that a piston maintained in contact with said curved wall moves substantially equal increments into or out of the chamber for equal increments of movement of rotation, each of said pistons being provided with a cam follower at another of its apexes, a single cam means cooperating with all of said followers and adapted to move a pair of diametrically opposed pistons into and out of a pair of diametrically opposed combustion chambers simultaneously, said cam means cooperating with said pistons to retain a third apex on each piston in contact with a peripheral wall throughout the excursion of the piston through the combustion chamber.
